UNITED STATES PATENT OFFICE

JOHN PACELLI, OF NEW YORK, N. Y.

SHOE-LAST.

1,111,317.

Specification of Letters Patent.

Patented Sept. 22, 1914.

Application filed June 7, 1912. Serial No. 702,248.

To all whom it may concern:

Be it known that I, JOHN PACELLI, a citizen of the United States, and resident of the borough of Brooklyn, in the city and State of New York, have invented a new and useful Improvement in Shoe-Lasts, of which the following is a specification.

My invention relates to an improvement in shoe lasts and more particularly to the construction of the heel where a considerable amount of pounding and hammering takes place in affixing the heel of the shoe to the sole, or when burnishing etc. the same.

The object of my invention is to provide a shoe last that will withstand this pounding without cracking or splitting, at the same time relieving the last supporting thimble from the shock of the blow.

A practical embodiment of my invention is represented in the accompanying drawings, in which,

Figure 1 represents a plan view of a shoe last with the heel plate partly broken away, and Fig. 2 represents a side elevation of the same, partly in section.

The shoe last, which is of the usual form, is denoted as a whole by 1, the heel portion by 2 and the cone or top by 3. The cone 3 is provided with a socket 4 for the reception 30 of a last supporting thimble 4* which is of usual construction and well known in the art.

The heel portion 2 is provided with a cavity 5 in which is placed a slightly resilient material 6, such, for instance, as leather, felt, fiber, hard rubber or any substance that has a slight degree of resiliency. In the present instance I have shown the material in layers, in which case I cement the 40 layers together by means of a resilient adhesive composition such as cork and glue, shown at 7. It will be understood that while I have shown two layers cemented together, I may use only one piece cemented in the cavity, or several layers may be used with or without cement. In using the resilient composition between the layers or in the cavity, I find it advantageous to use a harder and less resilient material than when there is no 50 adhesive composition used, because the composition will afford of itself a very considerable degree of resiliency. In fact, I may employ material of such hardness as to be practically non-resilient in combination with the resilient adhesive composition.

To cover and protect the cavity and material, a heel plate 8 of metal or other desired material may be provided, which plate may be secured to the heel by means of screws 9. The heel plate 8 may also be 60 provided with a hole 10, through which the lasting tacks are driven. Thus it will be seen that with my improved shoe last, any amount of pounding or hammering given to the heel will be absorbed by the resilient material 6 in the cavity 5, thereby relieving the shoe last of all shock or jar that would tend to split or crack it. Furthermore, by relieving the shoe last of any concussion, I 65 obviate the wear and tear on the socket 4, 70 by which the last is held in position for work.

It will be understood that the cavity 5 and resilient material 6 may be made larger or smaller according to the size of the last, 75 also the cavity may be of any shape, such as round or square.

It is obvious that various changes may be resorted to in the form and arrangement of the several parts without departing from 80 the spirit and scope of my invention; hence I do not wish to limit myself strictly to the structure herein set forth, but

What I claim is:

1. As an article of manufacture, a shoe 85 last provided with a shallow cavity in the bottom heel surface thereof, a resilient material filling said cavity and a plate secured to the last for covering and protecting said resilient material in the cavity. 90

2. As an article of manufacture, a shoe last provided with a shallow cavity in the bottom heel surface thereof, a resilient material and a resilient adhesive composition filling said cavity and a plate secured to the 95 last for covering and protecting said material in the cavity.

3. As an article of manufacture, a shoe last provided with a shallow cavity in the bottom heel surface thereof, a resilient adhesive in combination with other material filling said cavity and a plate secured to the last for covering and protecting said material in the cavity. 100

4. As an article of manufacture, a shoe 105 last provided with a shallow cavity in the bottom heel surface thereof, layers of resilient material filling said cavity and a plate secured to the last for covering and protecting said material in the cavity. 110

5. As an article of manufacture, a shoe last provided with a shallow cavity in the bottom heel surface thereof, layers of resilient material filling said cavity, a resilient adhesive composition interposed between said layers, and a plate secured to the last for covering and protecting said material in the cavity.

In testimony, that I claim the foregoing as my invention, I have signed my name in presence of two witnesses, this fifth day of June 1912.

JOHN PACELLI.
